COMBINED LAWN EDGER AND TRIMMER

Edward S. Hanson, Jr., Racine, Wis., and Raymond K. Strasel, Winthrop Harbor, Ill., assignors to Jacobsen Manufacturing Co., Racine, Wis., a corporation of Wisconsin

Application March 10, 1955, Serial No. 34,975

Term of patent 14 years

(Cl. D40—1)

Fig. 1 is a front perspective view of a combined lawn edger and trimmer showing our new design.

Fig. 2 is a reduced fragmentary perspective view taken from the right side of Fig. 1, but with certain parts thereof in a different position and with the tubular handles broken away.

Fig. 3 is an enlarged fragmentary perspective view taken from the right side of Fig. 1, but with certain parts thereof in another different position and with the tubular handles broken away.

We claim:

The ornamental design for a combined lawn edger and trimmer substantially as shown.
